[57] CLAIM

The ornamental design for table or the like, substantially as shown and described.

DESCRIPTION

FIG. 1 is a perspective view of a rectangular cocktail table showing one embodiment of my new design. The sides not shown are like the sides shown.

FIG. 2 is a perspective view of a square corner table showing another embodiment of my new design. The sides not shown are like the sides shown.

The design is characterized in the log-like appearance of the frame members and legs formed of corresponding cross-sectional size in combination with the inset tops disposed midway of the thickness of the surrounding frame, all as shown.
